UNITED STATES PATENT OFFICE.

WINTHROP L. JACOBS, OF EAST ORANGE, NEW JERSEY, ASSIGNOR TO THE
HARTFORD CARPET COMPANY, OF HARTFORD, CONNECTICUT.

DESIGN FOR A CARPET.

SPECIFICATION forming part of Design No. 13,669, dated February 27, 1883.

Application filed January 25, 1883. Term of patent 3½ years.

To all whom it may concern:

Be it known that I, WINTHROP L. JACOBS, of East Orange, Essex county, New Jersey, have invented a new and original Design for 5 Carpets, of which the following is a specification.

This invention relates to a new and original design for carpets and similar fabrics; and it consists in the novel grouping and configuration of figures hereinafter more fully described.

The accompanying photograph illustrates a face view of a carpet having my new design. The ground is broken up into irregularly-shaped figures each having its own peculiar 15 ornamentation and bordering, as is shown in the photograph. Over this ground is scattered

irregularly a system of gem and leaf-like ornaments connected in small groups, as shown, by short angular stems.

I claim—

1. The design for a ground for a carpet, consisting of the ground broken into variously shaped and ornamented figures, substantially as shown and described.
2. The design for a carpet, consisting of the 25 gem and leaf-like system, and the ground broken into variously shaped and ornamented figures, substantially as shown and described.

WINTHROP L. JACOBS.
